UNITED STATES PATENT OFFICE.

FRANK EDWARD SNYDER, OF MASSILLON, OHIO.

DRILL.

No. 902,008.

Specification of Letters Patent.

Patented Oct. 27, 1908.

Application filed February 7, 1908. Serial No. 414,716.

To all whom it may concern:

Be it known that I, FRANK EDWARD SNYDER, of Massillon, in the county of Stark and State of Ohio, have invented certain new and useful Improvements in Drills; and I do hereby declare the following to be a full, clear, and exact description of the invention, such as will enable others skilled in the art to which it appertains to make and use the same.

This invention relates to improvements in drills, and more particularly to such as are adapted for use in drilling coal, rock, metal, etc.

Many hand drills now in use comprise a threaded feed-bar or rod to which the drill and its chuck are rigidly secured, so that in use, by rotating this feed-rod, the drill is forced into the coal with a speed commensurate with the size of the thread on said bar, varying from eight to twelve threads per inch, depending upon the hardness of the material being drilled. Such a device requires a comparatively fine thread, as in drilling, hard spots in coal, such as sulfur, stone, etc., are often encountered and through which the drill could not be forced were the feed-rod provided with a coarse thread. The fine thread (V-shaped in cross-section) on the feed-rod causes considerable friction and soon wears out, frequently necessitating the recutting of the threads both on the feed-rod and in the thread box through which it passes. With a drill as heretofore constructed, on the lines above mentioned, it is often necessary when striking a hard spot in the coal, to remove the drill as it cannot be forced in further until the hard substance has been broken with a bit or long chisel and hammer, because the drill cannot be turned without feeding or turning the feed-rod.

The object of my present invention is to obviate the defects of drills as heretofore constructed and to so construct the device that the feed-rod can be operated without turning the drill bit.

A further object is to so construct the drill that, should the bit engage a hard spot or become dull so as to cause too much pressure against the feed-rod or upon the device, the actuating means for the feed-rod will be caused to rotate backwardly and said feed-rod to remain stationary; but fol-

low up and feed again as the drill bit (which continues to rotate), cuts its way clear.

55

A further object is to construct a drill in such manner that the feed-rod can be rotated without rotating the drill bit and thus enable the bit to be withdrawn in case of "clogging" and at the same time clean the hole of chips 60 which may have caused such clogging.

A further object is to construct the machine in such manner that the feed-rod and drill bit can be rotated simultaneously at different speeds or at the same speed.

65

A further object is to provide a drill in which the drill rod is rotatable in the feed-rod, which shall be capable of being manipulated in a manner to provide for all contingencies which may arise during the process of 70 drilling; and which shall be simple in construction, and easy to operate.

With these objects in view the invention consists in certain novel features of construction and combinations of parts as hereinafter 75 set forth and pointed out in the claims.

In the accompanying drawings, Figure 1 is a side elevation of a drill embodying my improvements. Fig. 2 is a view in end elevation and partly in section. Fig. 3 is a plan 80 view. Fig. 4 is an enlarged sectional view illustrating the gearing between the drill rod and feed-bar. Fig. 5 is a detail view of the actuating mechanism. Fig. 6 is a view of the gear housing. Fig. 7 is a view illustrating the manner of connecting the parts of the actuating mechanism to cause the feed-bar 85 and drill rod to rotate together at the same speed, and Fig. 8 is a view of an attachment to be used for operating the feed-bar independently of the drill-rod.

1 represents a standard or supporting post, to the lower end of which a cross-bar 2 is pivoted and provided at its ends with pointed feet 3 to engage the floor of a mine. The 95 standard 1 comprises two members 5-6, the upper member 5 telescoping into the tubular member 6 and held at any desired vertical adjustment by means of a pin 7 passing through holes in the member 6 and any one 100 of a series of holes 8 in the member 5. The upper member 5 of the standard is made with a threaded socket to receive a screw 9, the upper end of which terminates in a pointed pin 10 to engage the roof of the 105 mine. The screw 9 can be turned to clamp

the standard in position, by means of an arm or lever 11. In order to prevent the pin 7 from becoming lost it is attached to the standard by means of a chain 12.

5 A split sleeve 13 is adjustably secured to the standard 1 and is provided with a yoke 14 made integral therewith. The arms of the yoke 14 are provided with bearings 15 for trunnions 16 projecting laterally from a 10 housing 17 and these trunnions can be placed in position on the bearings 15 in the arms of the yoke through openings 18 in the tops of said arms. The housing 17 comprises two members hinged together and each member 15 is provided internally with threads to mesh with the threads of a tubular feed-rod or bar 19. The members of the two-part housing 17 are normally locked together by means of a bolt 20 pivoted to one member of the housing, passing between lugs 21 on the other member of said housing and provided with a 20 thumb nut 22 to engage said lugs.

The rear end of the feed-rod or bar 19 is made with a smooth portion upon which a 25 gear-housing 23 is loosely hung. This housing comprises two members bolted together and provided with depending projections which coöperate to form an arm 24. This arm may constitute a handle for a purpose 30 hereinafter explained and it also serves to receive the socketed upper end of a pin 25 secured thereto by means of a thumb-screw 26, and to the pin 25 a weight 27 is removably attached by means of a thumb screw 28,—said weight serving to maintain the 35 gearing housing 23 and the gearing therein, in proper position during the operation of the machine and at the same time permitting said housing and gearing to move forwardly during the feeding of the drill.

A gear-wheel 29 is secured to the smooth portion of the feed-rod or bar within the housing 23 and a smaller gear-wheel 30 is secured to the drill-rod 31 which passes through 45 and projects a short distance rearwardly beyond the feed-rod or bar 19. A short shaft 32 is mounted in the housing 23, parallel with the feed-bar and drill-rod, and to this short shaft two gears 33—34 are secured. 50 The gear 33 is approximately the same size as the gear 30 and meshes therewith, while the gear 32 is smaller and meshes with the gear 29. The several gears are protected by means of a gear-case 35 secured to the housing 23.

55 A chuck 36 is secured to the forward end of the drill-rod 31 for the reception of a bit 37. To the rear end of the drill-rod which projects beyond the rear end of the feed-bar and 60 gearing an operating handle or lever 38 is attached. This lever comprises two members adjustable longitudinally with relation to each other and secured at any desired adjustment by means of a threaded pin 39 and 65 thumb-nut 40. The free end of this adjust-

able operating lever is provided with a suitable hand grip 41. It is apparent that if it be desired to operate the machine by means of a motor, the latter may be connected by means of a flexible shaft or otherwise with 70 the rear end of the drill rod and the hand lever above described dispensed with.

From the construction and arrangement of parts above described it will be seen that when the operating lever is manipulated, 75 motion will be transmitted directly to the drill-rod for rotating the same and that simultaneously the feed-bar will be rotated through the medium of the gears at a slower rate of speed. During this operation the 80 gear-housing will be maintained pendulous on the feed-rod by the action of the weight 27, but, as is apparent, may travel forwardly with the feed-rod during the operation of the machine. If, during the drilling 85 operation the drill-bit should become stuck on account of the clogging of chips in the hole being bored, the gear-housing can be revolved so as to transmit through the gearing a backward rotation of the feed-rod without 90 rotating the drill-rod, and thus the bit may be withdrawn from the hole and the chipings which caused the clogging removed at the same time. To facilitate such operation of the gear-housing, the weight 27 may be removed and the arm 24 used as a handle,—or if desired a hand-wheel 42 may be attached to the gear-housing and to facilitate such attachment the hand-wheel 42 is provided with a socketed block 43 which is 95 revolvably attached to the arm 24.

If, during the normal operation of the machine, the drill bit should engage a very hard spot in the material or become dull so as to cause too much pressure on the feed-bar or 105 undue strain on the machine, the gear-housing will revolve backwardly and cause the feed-bar to remain stationary, but as soon as the hard spot shall have been penetrated by the bit, the feed-bar will resume its function, 110 the resistance which had caused the gear-housing to revolve backwardly having now been removed and said gear-housing permitted to hang on the feed-bar. Should the material being drilled be of more than average hardness, the gear-housing can be maintained in its proper pendulous position by adjusting the weight 27 downwardly on the pin 25 to give the necessary pressure or strength of feed.

115 Assuming that the feed-bar 19 has four threads per inch and that the gears are such that the feed-bar revolves once while the drill-rod makes two revolutions (the gear-housing remaining stationary), the machine 125 will feed one inch in eight turns of the operating lever 38. Should the operator not wish to use the weight 27 he can remove it and by holding the arm or handle 24 the device will feed one inch in eight turns of the 130

crank or lever 38, and if at any time there is too much strain on the device or its operation is too hard, the crank or lever 38 can be released occasionally by the operator and 5 the housing 23 thus allowed to revolve backwardly and stop the feed until the drill-bit has cut its way and the excessive pressure thereby removed. The operator may then hold the gear-housing 23 by means of the 10 handle 24, thus regulating the pressure or feed at will. Thus it will be seen that the machine can be caused to feed continuously or at intervals, to suit the work.

The pendulous housing will cause the operation of the machine to be effected in the manner above explained when the machine is disposed in a position which is horizontal or approximately so. When however, it is necessary to dispose the drill in a position 15 approximating the vertical, the automatic action of the weight 27 in controlling or regulating the feed, becomes ineffectual. In such case it will be necessary for the operator to hold the gear-housing 23 in proper position and this may be readily accomplished 20 by means of the arm or handle 24 or by means of the hand-wheel 42 attached to said gear-housing in the manner hereinbefore explained. By holding the handle 24 or the 25 hand-wheel 42, the device must feed at whatever speed it is geared, but by releasing said handle or hand-wheel so as to allow the gear-housing 23 to revolve backwardly as the pressure becomes too strong or the operating 30 lever turns too hard, the device can be controlled perfectly and the pressure or feed increased or diminished, as occasion may require.

Incident to the construction of my improved drill, I am enabled to use a very coarse thread on the feed-bar and control the speed of feed by varying the size of gears 32-34, which makes the device quite durable and easy to operate. As the feed-bar 40 and drill-rod can be operated independently I am enabled to control the feed to suit all kinds of work with the same machine. When turning the operating crank or lever the drill rod turns also whether the feed-rod 45 is rotated or not, and thus there is little chance for the drill-bit to become clogged in the hole being drilled, as by stopping the feed and continuing to turn the drill-rod, the bit will clear itself.

Should it be desired to use the machine in any substance which is soft enough to permit the full feed of the feed-bar to be transmitted to the drill-rod,--this may be accomplished by removing the weight 27 from the 50 housing and attaching to the arm 24 a fork 44 which is made to embrace the operating crank or lever 38. By now operating the crank or lever 38 the feed-bar and the drill-rod will be caused to rotate together at the 55 same speed and thus the full feed of which

the feed-bar is capable is transmitted to the drill-rod.

Having fully described my invention what I claim as new and desire to secure by Letters-Patent, is,—

1. In a drill, the combination with a threaded housing and a tubular threaded feed-bar passing through the same, of a drill rod extending through the tubular feed-bar, gears on the feed-bar and drill-rod, 75 a gear-housing loosely mounted on and supported by the feed-bar, and gears supported by said housing and in constant mesh with the gears on the feed-bar and drill-rod.

2. In a drill, the combination with a 80 threaded housing and a tubular threaded feed-bar passing through the same, of a drill-rod passing through the feed-bar, a pendulous device mounted on the feed-bar, gears carried by said pendulous device and 85 gears secured respectively to the feed-bar and drill-rod and meshing with the gears carried by the pendulous device.

3. In a drill, the combination with a threaded housing and a tubular threaded feed-bar passing through the same, of a drill-rod passing through the feed-bar, a gear-housing mounted loosely on the feed-bar, connected gears carried by said housing, 90 gears on the feed-bar and drill-rod and meshing with said connected gears, and a weight adjustably attached to the lower end of said gear-housing.

4. In a drill, the combination with a threaded housing and a tubular threaded feed-bar passing through the same, of a drill-rod passing through the feed-bar, a gear-housing mounted loosely on the feed-bar and capable of rotation thereon, connected gears 100 carried by said gear-housing, gears secured respectively to the feed-bar and drill-rod and meshing with said connected gears, and operating means attached to the drill-rod.

5. In a drill, the combination with a threaded housing and a tubular threaded feed-bar passing through the same, of a drill-rod passing through the feed-bar, a pendulous device mounted loosely on the feed-bar, connected gears carried by said pendulous device, 110 gears secured respectively to the feed-bar and drill-rod and meshing with said connected gears and detachable means for permitting the feed-bar and drill rod to be rotated simultaneously at the same speed.

6. In a drill, the combination with a 120 threaded housing and a tubular threaded feed-bar passing through the same, of a pendulous device mounted loosely on the feed-bar, connected gears carried by said pendulous device, a drill-rod passing 125 through the tubular feed-bar, gears secured respectively to the feed-bar and drill-rod and meshing with said connected gears, an operating lever secured to the drill-rod and detachable means for connecting said pendu- 130

lous device with the operating lever to cause rotation of the feed-bar and drill-rod simultaneously at the same speed.

7. In a drill, the combination with a threaded housing and a tubular threaded feed-bar passing through the same, of a drill-rod passing through the feed-bar, operating means secured to said drill-rod, a gear secured to the drill-rod, a gear secured to the feed-bar, a pendulous device mounted loosely on the feed-bar, connected gears carried by said pendulous device, and means for weighting the lower end of said pendulous device.

8. In a drill, the combination with a threaded housing and a tubular threaded feed-bar passing through the same, of a drill-rod rotatable in said feed-bar and passing through the same, an operating lever secured

to the drill-rod and comprising a plurality of members, adjustable longitudinally with relation to each other, gears secured respectively to the feed bar and drill-rod, a pendulous device mounted loosely on the feed-bar, connected gears carried by said pendulous device and meshing with the gears on the feed-bar and drill-rod, a weight, and means for adjustably attaching said weight to the pendulous device.

In testimony whereof, I have signed this specification in the presence of two subscribing witnesses.

FRANK EDWARD SNYDER.
